UNITED STATES PATENT OFFICE.

HENRY S. JENNE, OF ROCHESTER, NEW YORK, ASSIGNOR TO JOHN G. ELBS, OF ROCHESTER, NEW YORK.

EGG-CARRIER.

1,128,148.

Specification of Letters Patent.

Patented Feb. 9, 1915.

Application filed March 29, 1912. Serial No. 687,190.

To all whom it may concern:

Be it known that I, HENRY S. JENNE, of Rochester, in the county of Monroe and State of New York, have invented certain new and useful Improvements in Egg-Carriers; and I do hereby declare the following to be a full, clear, and exact description of the same, reference being had to the accompanying drawings, forming part of this specification, and to the reference-numerals marked thereon.

My invention relates to egg carriers, and it has for its object to provide a convenient container for transporting eggs in small quantities, as by the dozen, and which may be formed readily from a flat blank.

A further object of my invention is to provide a carrier of such construction as to permit the eggs to be inspected or candled without removing them from the container.

Still another object of the present improvement resides in providing a seal for the carrier, so that, if desirable, when the cover is closed, the box can not be opened without breaking or destroying some portion of the same.

To these and other ends the invention consists in certain improvements and combinations of parts, all as will be hereinafter more fully described, the novel features being pointed out in the claims at the end of the specification.

In the drawings: Figure 1 is an elevation of the blank from which the carrier, as disclosed in the present embodiment, is formed; Fig. 2 is a view in elevation, showing the blank partially folded, with the egg cells in position, the cover section being thrown back; Fig. 3 is a view in end elevation of the carrier, when closed; Fig. 4 is a sectional view on the line 4^a—4^a of Fig. 2, with the cover closed; Fig. 5 is a similar view, on the line 5^a—5^a of Fig. 2; Fig. 6 is a sectional view taken on the same line as Fig. 4, and showing the cover section removed to permit the eggs to be inspected, and Fig. 7 is a sectional view on the line 7^a—7^a of Fig. 2.

Similar reference numerals throughout the several figures indicate the same parts.

The present embodiment illustrates one method of carrying my invention into effect and comprises a single blank, formed of paper board or other flexible material adapted to be folded. The blank, when unfolded,

appears as shown in Fig. 1, and includes a cell-carrying section 1, to which the cell forming partitions 2 are attached by means of the slits 3. The partitions 2, are arranged transversely, as shown, while 4 60 designate longitudinal partitions which co-operate with said partitions 2 to form the egg cells. The blank further comprises the bottom section 5 and cover section 6, while 7 designate the side sections, that is to say, 65 the sections of the blank which form the exterior sides of the box when folded.

I desire to provide means for inspecting or candling the eggs without removing them from the carrier, in order to permit 70 the dealers who receive eggs in large quantities already packed, to examine them before selling to a customer, and to this end, the blank is preferably provided with the section 8, which for convenience I term the 75 candling section, adapted to lie between the bottom edges of the cell forming partitions and the bottom section 5 when the blank is folded. The candling section thus constitutes a supplemental bottom for the egg cells, 80 and serves to hold the eggs when the cover is removed, as in Fig. 6. The section 8 has formed therein the several openings 9 to permit the eggs to be inspected over a suitable light, in a dark room, as usual when 85 candling. It is desirable to provide means for holding the candling sections in engagement with the cell forming partitions, and to this end, the section 8 includes the wall 10 having projecting portions 11 which are 90 arranged to engage the recesses 11^a in the longitudinal partition 4 and to overlie said partitions, as shown in Figs. 2, 4 and 7. It will be noted that the projecting portions 11 are disposed beneath the upper edge of 95 the partition 4, as shown in Fig. 7, and thus serve to prevent longitudinal movement of the cell forming partitions as well as to hold the candling section, or supplemental bottom in engagement with the egg cells, 100 whereby to support the eggs when the cover is removed.

While I have described my invention as embodying the candling section 8, it will be obvious that this may be omitted, if it is 105 desired to produce a cheaper or simpler carrier. In such cases, in order to retain the egg cells against longitudinal movement, the blank may be formed with a cut out or attached portion or flap 12 which engages 110

between the adjacent transverse partitions of the egg cells and serves to lock the partitions against movement relatively to the blank. In the present embodiment, the 5 candling section 8 is provided with a cut away portion or opening 13 through which the flap 12 projects, and it will be apparent that both the flap 12 and projecting portions 11 may be employed in the same structure, although preferably, these are alternative locking means to be used with or without the candling section, according to the particular requirements.

The transverse partitions of the egg cells 15 may be formed with triangular portions 14 cooperating with the longitudinal walls so as to afford spaces or air chambers at the sides of the box which protect the eggs, and prevent their being subjected to any undue 20 jarring or shaking during shipment.

The cover section 6 is preferably provided with the extension 15 having beveled ends 16 and V-shaped notches 17 which cooperate with the beveled portions 18 of the 25 transverse partitions 2, so as to effect the ready centering and positioning of the cover, and stabilizing it when closing the box.

In order to seal the box to prevent any 30 unauthorized opening, I may provide a catch 19 on the extension 15, said catch being preferably formed of spring metal and arranged to engage a suitable notch in the side of the box. To this end, the cell 35 carrying section 1 may be provided with the opening 20, within which the catch 19 engages, when the box is closed, as shown in Fig. 5. With this locking means, after the box is once closed, it can not be opened 40 without breaking or tearing some portion, to release the catch 19. Such a locking means, while possessing certain advantages, is not essential, and it is to be understood

that the other parts of my invention may be used without this, when desired.

The particular construction herein set forth and described may be otherwise modified, without departing from the essential features of my invention, and in the present application, I desire to include any such 50 changes as may come within the scope of the claims hereinafter.

I claim as my invention:

1. In an egg carrier, the combination with a foldable blank having a cell-carrying section, of a plurality of separate cell forming partitions removably secured to said section, the blank having a bottom section, a candling section adjacent to the cell-carrying section and adapted to lie between 60 the bottom section and the cells, projecting portions formed on the candling section and adapted to engage one of the cell-forming partitions, and a cover section.

2. In an egg carrier a foldable blank having a cell carrying section, said section being slotted to receive transverse cell-forming partitions, the blank having a bottom section and a cover section adapted to enclose the cells formed by the partitions, and 70 a cut-out portion formed on the blank and arranged for engagement with one of said transverse partitions.

3. In an egg carrier, a foldable blank having bottom, cover, and side sections, a 75 cell carrying section arranged adjacent to one of said side sections and provided with slots to receive cell-forming partitions, a candling section adjacent to the cell carrying section, and means for holding the 80 candling section in engagement with the egg cells.

HENRY S. JENNE.
